EUGENE RILEY EDSON, OF CLEVELAND, OHIO.

RENDERING-TANK.

SPECIFICATION forming part of Letters Patent No. 723,850, dated March 31, 1903.

Application filed November 17, 1902. Serial No. 131,719. (No model.)

To all whom it may concern:

Be it known that I, EUGENE RILEY EDSON, a citizen of the United States of America, residing at Cleveland, in the county of Cuyahoga and State of Ohio, have invented certain new and useful Improvements in Rendering or Reducing Tanks or Receptacles; and I hereby declare the following to be a full, clear, and exact description of the invention, such as will enable others skilled in the art to which it pertains to make and use the same.

This invention relates to improvements in jacketed rendering or reducing tanks or receptacles, and more especially to a tank or receptacle of the character indicated which is provided centrally and interiorly with a vertically-arranged drum depending and removably secured to the top or upper head of the receptacle and provided with an interior chamber, which is in open relation at the upper and lower ends of the drum with the chamber of the external jacket of the said receptacle.

The primary object of this invention is to provide a jacketed tank or receptacle in which, first, an inner vertically-arranged cylindrical metal shell, which forms the surrounding wall of the main interior chamber of the receptacle and also forms the inner side wall of the chamber of the jacket of the receptacle, can elongate downwardly from expansion by heat or shorten or contract upwardly upon cooling independently of the outer side wall of the jacket-chamber without in any wise affecting the operativeness of any portion of the receptacle or unduly straining any part of the receptacle, and, second, in which the interior drum, which depends from and is removably attached to the top or upper head of the receptacle, is capable of elongating downwardly from expansion by heat or shortening or contracting upwardly upon cooling independently of the corresponding expansion or contraction, as the case may be, of the aforesaid inner shell.

With this object in view and to the end of realizing other advantages hereinafter appearing the said invention consists in certain features of construction and combinations of parts hereinafter described, and pointed out in the claims.

The accompanying drawing is a side eleva-

tion, largely in central vertical section, of a rendering or reducing tank or receptacle embodying the said invention.

Referring to the drawing, *a* designates an inner vertically-arranged cylindrical metal shell which forms the main interior chamber *b* of the tank or receptacle, in which chamber the material which is to be reduced or rendered is digested or treated. The shell *a* is shaped at its lower end to form a downwardly-discharging opening or outlet *c* for the chamber *b*, which outlet *c* is arranged centrally of the lower end of the said chamber and has an upwardly-flaring mouth *d*, which is formed by the inverted-cone-shaped lower end portion *e* of the shell *a*. The surrounding wall *f* of the outlet *c*, below the mouth of the said outlet, is cylindrical, and the said outlet is normally closed at its lower or outer end by a suitably-applied door *g*, which is opened whenever required to accommodate the passage of any material from within the chamber *b* through the outlet *c* of the said chamber. The shell *a* forms also the inner side wall of the chamber *h* of the external jacket of the receptacle, and the outer side wall of the said jacket-chamber is formed by a vertically-arranged outer cylindrical metal shell *l*, which is of course considerably larger transversely than and surrounds the inner shell *a*. The outer shell *l* has a lower inverted-cone-shaped portion *m*, which surrounds and is transversely larger than the correspondingly-shaped lower end portion *e* of the shell *a*, so that the chamber of the jacket extends downwardly to and around the upwardly-flaring mouth of the outlet *c* of the chamber *b*. The lower end portion *m* of the shell *e* is provided at its lower end with a suitably-applied stuffing-box *o*, which surrounds the surrounding wall *f* of the outlet *c*, below the flaring mouth of the said outlet, and forms a fluid-tight joint around the said wall, and the chamber *p*, which is formed in the upper portion of the said wall *f*, is open at its upper end and forms a downward enlargement of the chamber of the jacket. The wall *f* is provided with a port *r*, which extends downwardly from and communicates with the chamber *p* and is in open relation at its lower end with a drain-pipe *s*, which has a normally closed valve *t*. The shell *l* is provided also with a pipe *u*, which communicates with the chamber *h* and

is employed to conduct fluid into the said chamber. The pipe *u* is provided with a valve *w*.

Both shells *a* and *l* are secured at their upper ends to the top or upper head *x* of the receptacle, which head is instrumental in closing the upper end of the chamber *b* and extends snugly between and is secured to the upper ends of the said shells; but the inner shell *a* is free to elongate downwardly through the stuffing-box *o* independently of the outer shell *l*.

A closed interiorly-chambered or hollow drum *y* is arranged vertically within and centrally of the chamber *b* and depends from the head *x* into the lower portion of the said chamber and is free to elongate downwardly. The drum *y* is removably secured at its upper end to the head *x* and is shown provided at its said end with an external annular flange *j*, and screws *k*, which have their heads abutting against the under side of the said flange, extend through the flange into correspondingly-screw-threaded holes *n*, formed in the under side of the said head.

A curved copper pipe *A* is arranged within the upper portion of the chamber *b* and is applied in any approved manner to place it into communication at one end with the jacket-chamber *h* and in open relation at its opposite end with the interior chamber of the drum *y*. A curved copper pipe *B* is arranged within the lower portion of the chamber *b* and applied in any approved manner, so that it at one end communicates with the chamber *h* and at its opposite end is in open relation with the interior chamber of the drum *y*. The pipes *A* and *B* are instrumental in forming passage-ways between the jacket-chamber *h* and the interior chamber of the drum *y*.

An air-conducting pipe *D* is arranged centrally of and extends longitudinally through the drum *y* and below the lower end of the said drum terminates in a foraminated head *G*, which is removably attached to the said pipe, having interior screw-threads which engage with corresponding screw-threads formed on and exteriorly of the said pipe.

A tubular washer *H*, of compressible and elastic material—such, for instance, as cork or rubber—is tightly interposed between the head *G* and the exterior of the lower head of the drum *y* and prevents the leakage of fluid between the chamber of the drum and the chamber *b*. The head *G* forms, therefore, a nut for tightening the washer *H*, as well as an air-charging head for the pipe *D*. A nut *K* engages with corresponding screw-threads formed on and exteriorly of the pipe *D* at and next to the inner side of the lower head of the drum *y* and is consequently arranged to form a stop, which prevents downward displacement of the said pipe independently of the drum, so that a snug interposition of the washer *H* between the said head of the drum and the air-discharging head *G* of the pipe is maintained. The pipe *D* extends above the

head *x* a suitable distance and externally of the receptacle is connected and placed in open relation by a hose or flexible tube *v* with the outlet of a suitably-operated air-pump *L*. The head *x* is provided with a stuffing-box *R* around the pipe *D*, so as to prevent leakage of fluid between the interior chamber of the drum and the external atmosphere where the said pipe extends through the said head.

The head *x* is provided at one side of the drum *y* with an upwardly-flanged charging-aperture *T*, through which the material which is to be rendered or reduced or treated within the chamber *b* is fed to the said chamber, and a suitably-applied cover *U* is provided for closing the said aperture. The aperture *T* is large enough transversely to accommodate the passage of the drum *y* therethrough in the assemblage or renewal of parts.

The lower inverted-cone-shaped end portion *m* of the outer shell *l* of the jacket is provided exteriorly with an annular flange *W*, which is adapted to rest upon a base or support. (Not shown.)

The hereinbefore-described construction, it will be observed, is simple and durable and more especially convenient so far as the assemblage and renewal of parts are concerned, and it is obvious that the interior drum *y* can elongate downwardly from expansion by heat or contract by cooling independently of the metal shells *a* and *l*; that the inner shell *a* can elongate downwardly from expansion by heat or contract by cooling independently of the drum and the outer shell *l*; that the jacket-chamber *h* extends into the wall *f* of the outlet *c* of the main chamber *b*, below the flaring mouth of the said outlet, and consequently the said wall is directly heated from any heating fluid supplied to the said jacket-chamber, and that the pipe *D* can shift downwardly with a downward elongation of the drum without leakage between the upper end of the said drum and the external atmosphere and without loosening of the washer *H*.

What I claim is—

1. A jacketed rendering or reducing tank or receptacle comprising the following: an inner vertically-arranged metal shell forming the surrounding wall of the main interior chamber of the receptacle and provided, at its lower end and centrally, with a downwardly-discharging opening or outlet having an upwardly-flaring mouth; an outer vertically-arranged metal shell forming the outer side wall of the jacket and surrounding and larger transversely than the aforesaid inner shell and provided, at its lower end, with a stuffing-box which surrounds the surrounding wall of the aforesaid outlet; a top or upper head instrumental in closing the upper end of the aforesaid chamber and provided with a charging-aperture, which head extends snugly between and is secured to the aforesaid shells; a drum arranged vertically and

- centrally of the said chamber and depending from and removably secured to the aforesaid head; passage-ways between the interior chamber of the said drum and the chamber of the jacket; an air-conducting pipe extending centrally and longitudinally of and through the said drum and through the aforesaid head and discharging below the drum into the aforesaid chamber; means for supplying air to the said pipe; a stuffing-box surrounding the said pipe where the pipe extends through the aforesaid head; means for supplying fluid to the chamber of the jacket, and means for draining the said jacket-chamber.
- 15 2. A jacketed rendering or reducing tank or receptacle comprising the following: an inner upright metal shell forming the main interior chamber of the receptacle and provided, at its lower end, with a downwardly-discharging opening or outlet; an outer upright metal shell instrumental in forming the jacket and surrounding and larger transversely than the aforesaid inner shell and provided, at its lower end, with a stuffing-box which surrounds the surrounding wall of the aforesaid outlet; a top or upper head instrumental in closing the upper end of the aforesaid chamber and provided with a charging-aperture, which head is secured to the aforesaid shells; an upright drum arranged centrally of the said chamber and depending from and removably secured to the said head; a passage-way between the interior chamber of the said drum and the chamber of the jacket; means for supplying fluid to the chamber of the jacket, and means for draining the said jacket-chamber.
- 30 3. A jacketed rendering or reducing tank or receptacle comprising the following: an outer upright metal shell forming the jacket; an inner upright metal shell forming the main interior chamber of the receptacle and surrounded by and smaller transversely than the aforesaid outer shell and provided, at its lower end, with a downwardly-discharging opening or outlet and free to elongate downwardly independently of the said outer shell; a stuffing-box arranged to form a fluid-tight joint between the lower ends of the said shells, and a top or upper head instrumental in closing the upper end of the aforesaid chamber and provided with a charging aperture, which head is secured to the aforesaid shells.
- 45 4. A jacketed rendering or reducing tank or receptacle comprising the following: an inner upright metal shell forming the main interior chamber of the receptacle and provided, at its lower end, with a downwardly-discharging opening or outlet which has an upwardly-flaring mouth; an outer upright metal shell instrumental in forming the jacket and surrounding and larger transversely than the aforesaid inner shell and provided, at its lower end, with a stuffing-box which surrounds the surrounding wall of the aforesaid outlet; a chamber formed in the upper end of
- the said wall and extending around the said outlet and forming a downward enlargement of the chamber of the jacket; means for supplying fluid to the jacket-chamber, and a valved drain-pipe in open relation with and arranged to drain the lower end of the aforesaid downward enlargement of the jacket-chamber.
- 55 5. A rendering or reducing tank or receptacle comprising the following: an upright metal shell forming the main interior chamber of the receptacle and provided, at its lower end, with a downwardly-discharging opening or outlet; a top or upper head instrumental in closing the upper end of the said chamber and provided with a charging-aperture, which head is secured to the aforesaid shell, and a drum arranged centrally of the said chamber and depending from and removably secured to the aforesaid head and free to elongate downwardly.
- 70 6. A rendering or reducing tank or receptacle comprising the following: an upright metal shell forming the main interior chamber of the receptacle and provided, at its lower end, with a downwardly-discharging opening or outlet; a top or upper head instrumental in closing the upper end of the said chamber and provided with a charging-aperture, which head is secured to the aforesaid shell; an interiorly-chambered drum arranged centrally of the said chamber and free to elongate downwardly and provided, at the upper end, with an external flange removably secured to the under side of the aforesaid head, and means for supplying fluid to the interior chamber of the drum.
- 75 7. A rendering or reducing tank or receptacle comprising the following: an upright metal shell forming the main interior chamber of the receptacle and provided, at its lower end, with a downwardly-discharging opening or outlet; a top or upper head instrumental in closing the upper end of the said chamber and provided with a charging-aperture, which head is secured to the aforesaid shell; an interiorly-chambered closed drum arranged centrally of the said chamber and depending from and removably secured to the aforesaid head and free to elongate downwardly; means for supplying fluid to the interior chamber of the drum; an air-conducting pipe extending longitudinally of and through the drum and through the aforesaid head and discharging below the drum into the aforesaid chamber; means for supplying air to the said pipe, and a stuffing-box surrounding the said pipe where the pipe extends through the aforesaid head.
